UNITED STATES PATENT OFFICE.

ALBERT D. FENWICK, OF PHILADELPHIA, PENNSYLVANIA, ASSIGNOR TO
THE FENWICK COLLAR AND CUFF MACHINE COMPANY, OF PORTLAND,
MAINE.

SEWING-MACHINE GUIDE.

SPECIFICATION forming part of Letters Patent No. 599,444, dated February 22, 1898.

Application filed July 8, 1897. Serial No. 643,829. (No model.)

To all whom it may concern:

Be it known that I, ALBERT D. FENWICK, of Philadelphia, county of Philadelphia, and State of Pennsylvania, have invented an Improvement in Sewing-Machine Guides, of which the following description, in connection with the accompanying drawings, is a specification, like letters and figures on the drawings representing like parts.

10 This invention has for its object the production of a guide more especially adapted to be used in connection with a sewing-machine when stitching together collars, cuffs, wristbands, neckbands, &c.

15 My improved guide contains several movable members, as a main and auxiliary edge-gage and a combined band and top guide, each of which has its own appropriate work to do in the production of each collar, and these 20 parts are so connected and combined that they may be quickly brought into their proper operative positions without loosening any screws or making any adjustments.

In the production of a turn-over collar the 25 material comprising the band must be united at its ends and at what is to constitute the lower edge of the band and then the top part of the collar must be guided and inserted into the space between the open plies at the top 30 of the band.

Figure 1 shows in side elevation part of a sewing-machine frame with one of my improved collar-guides in position; Fig. 2, a top or plan view of the bed-plate and presser-foot 35 with my guide attached for turn-over-collar work as it will appear when starting to stitch together the plies of the band; Fig. 3, a like view showing the parts changed in position, as when putting in the top of the collar. Fig. 40 4 shows my improved guide in position for stitching one part of a stand-up collar. Fig. 5 shows the said parts in another position, as when in the reentering corner at the junction of the top with the lower part of said collar; 45 and Fig. 6, an enlarged side elevation of the top and band guide.

The bed-plate A, overhanging arm A', needle-bar B, needle b, and presser-foot b' are and may be all of any usual or suitable kind.

50 My novel guide presents a base c, which may

be provided with any usual slot c' for the reception of a clamp-screw c², by which to confine the base in adjusted position on the usual bed. The base has a stud-screw d, on which is pivoted an arm or lever d', having, as shown, a knob d², and said lever has its acting end convexed to form a main edge-gage d³, and the end of said arm or lever most remote from said end d³ has jointed to it at d⁴ a hook d⁴, which is adapted to be readily engaged with or disengaged from a post e. (Shown best in Figs. 4 and 5.) The hook is shown in engagement with said post in Figs. 1 to 3, and a spring d⁵, attached to the hook and bearing on the post, serves to hold the hook in engagement with the post; but in Figs. 4 and 5 this hook is disengaged from the post e and is engaged with a post f. (Shown best in Figs. 2 and 3.)

The base c has secured to it a locking device g to hold the lever d in its inoperative position, (see Figs. 3 and 5,) it then being turned aside to permit other parts of the attachment to be put into operative position.

The post e rises from an arm e', attached to a slide-bar e², provided at its front end with a peculiar-shaped combined band and top guide, (shown best in Fig. 1 and enlarged in Fig. 6,) said guide having two open mouths 2 3, in which will be inserted, respectively, 80 against the walls 4 5 two parts of the open top edge of the collar-band h, (shown by dotted lines in Fig. 3,) while the top of the collar to be presented between the open upper edge of the band is inserted in the space 6 with its 85 edge against the wall 7.

The post f rises from a bar f', having at its acting end a downturned finger f², (shown best in Fig. 1 and by dotted lines in the other figures,) said finger constituting an auxiliary 90 edge-gage.

The bar f', carrying the auxiliary edge-gage, is made movable toward and from the presser-foot only in a straight line, and when the main pivoted edge-gage d³ is in its operative position the auxiliary edge-gage lies directly under the bar d', the bar d' carrying this edge-gage at each time it lies back away from the presser-foot.

Referring to Fig. 2, the main edge-gage d³ 100

- is shown in operative position, and the auxiliary edge-gage f^2 is directly in line with the operative part of the main edge-gage and below the lever d' , carrying the main edge-gage, 5 so that when the main edge-gage is turned aside the auxiliary edge-gage is obliged only to move in a direct line into its operative position, and it is not obliged to wait at all for the lever d' to get out of the way.
- 10 In use let it be supposed that a turn-over collar is to be stitched together. The operator will take the two or more plies to enter into the band, they having their edges in-turned, and will lay the said plies together 15 with their inturned edges against each other, and in this condition the band will be put under the presser-foot, as shown in Fig. 2, the edges of the said material being put against the main edge-gage d^2 , and the stitching will 20 preferably be started at the upper edge of the band at a distance from its end equal to the distance it is desired that the end of the band shall project beyond the end of the top of the collar. The stitching will be run from this 25 point to the end of the band, then across the end of the band, and along the lower edge of the band and across the other end. This operation leaves the most of the top of the band open, and now the top of the collar must be 30 stitched into this open part between the two or more plies of the band. Prior, however, to this latter operation, the band is removed from the machine and is turned over and turned end for end, so as to again put into 35 position under the needle that part of the band at which the stitching referred to and already made in the band was started. The operator takes hold of the knob d^2 and turns the lever d' aside and puts it into the holding 40 device g , and in doing this the hook d^4 in engagement with the post e acts to slide forward the bar e^2 , putting the combined band and top guide into position at the needle, as shown in Fig. 3, and then the lower and upper parts 45 of the open band will be put into the spaces 2 and 3, (see Fig. 6,) and then the top of the collar will be put into the space 6, the end of the top part of the collar farthest from the operator being put against the stitches holding together the top of the band, the stitches 50 first made in the upper edge of the band at a short distance from its end, and then the machine is started, the stitching commencing at the point referred to and passing through not 55 only the band but also the top of the collar, and the material is fed, say, away from the operator while the stitching is followed along the top of the band to the end of the top, when the lever d is again turned to put the 60 end d^2 of the main gage in working position, and at the same time withdrawing the combined band and top guide, and the end d^2 acts to guide the band while stitching from the end of the top to the end of the band. 65 When my attachment is used to stitch standing collars or cuffs, the combined band

and top guide is not then to be used, and for such work the hook d^4 is disengaged from the post e and is engaged with the post f , as in Figs. 4 and 5.

70

The stitching for a standing collar will preferably be commenced near the end of the lower edge of the collar, as best shown in Fig. 4, and at that time the edge of the main gage d^2 will be in its operative position. From the 75 position Fig. 4 the collar will be fed in the direction of the arrow, and when the stitching reaches the corner 10 the machine will be stopped, and the main edge gage will be turned into its inoperative position, Fig. 5, 80 thus putting the auxiliary gage f^2 into position to receive against it the end 12 of the collar as the stitching is being done across the end and about the corner 13 into the small re-entering angle 14 at the junction of the bottom and top parts of the collar, said auxiliary gage remaining in such position until the stitching arrives at the upper corner 15 of the collar, when the main gage d^2 will be again 85 turned into operative position, and it in its 90 movement will put the auxiliary gage into its inoperative position, (see Fig. 4,) and the stitching will be continued, using the main gage d^2 along the top edge of the collar until the opposite end of the top corresponding to 95 corner 15 is reached, when the machine will be again stopped, and the position of the main gage will be again changed, leaving the gage f^2 in position while the end of the collar and part of the bottom part of the collar next to 100 the upright edge of the end and about the end is being stitched. Fig. 5 of the drawings shows the collar in this last position, and having stitched across the end 12 of the collar, the end opposite the point 12, the main gage d^2 105 is again put into operative position to guide the lower edge 17 of the collar while it is being stitched to the point where the stitching commenced.

110

Having described my invention, what I claim as new, and desire to secure by Letters Patent, is—

1. In a guide of the class described, a base, a main edge-gage d^2 , a combined band and top guide for receiving the band and top from 115 opposite sides and maintaining the plies thereof properly superposed for stitching together, and connections between said main edge-gage and the combined band and top guide, whereby when one is put into working position the 120 other may be automatically put into its inoperative position, and vice versa, substantially as described.

125

2. A main edge-gage for use in stitching together collars and the like, it consisting of a 130 base, a lever pivotally mounted on said base and provided at one end with an edge-gage d^2 , and a combined band and top guide, and jointed connections between said lever, and said combined band and top guide, whereby by movement of the said lever it may be put into or out of operative position, and the com-

bined band and top guide be moved simultaneously with the said lever, substantially as described.

3. In a guide of the class described, a main edge-gage laterally movable into inoperative position, combined with an auxiliary edge-gage longitudinally movable into operative position, the latter when in its inoperative position lying underneath the main edge-gage, whereby the auxiliary gage may be moved directly into operative position without interference by or with the main gage and a connection between the main edge-gage and said auxiliary edge-gage, substantially as described.

4. In a gage of the class described, a main edge-gage, made as a lever, an independent auxiliary edge-gage, and connections between and pivoted to the said main and the said auxiliary edge-gage whereby when the main edge-gage is put into its operative position the auxiliary edge-gage is put into its inoperative position, and vice versa, substantially as described.

25 5. In a gage of the class described, a base, a pivoted main edge-gage, a locking device to hold the said main edge-gage in its inoperative position, and a combined band and top guide, combined with means to removably

connect the said main edge-gage with the combined band and top guide, to operate substantially as described.

6. In a guide for collars and like work, a base, a main edge-gage pivotally mounted thereon, and a combined band and top guide arranged to be slid back and forth longitudinally on said base; combined with connections between said pivoted main edge-gage, and said band and top guide, whereby the turning of said main edge-gage on its pivot effects the sliding of said combined band and top guide into and out of operative position as required, substantially as described.

7. A guide for collars and like work, comprising a plurality of independently-movable gage members, said members being independent and one of them being provided with means for moving the remaining members as it is moved, said means being arranged to co-operate with either of the remaining members, as desired.

In testimony whereof I have signed my name to this specification in the presence of two subscribing witnesses.

ALBERT D. FENWICK.
